COOKING RANGE HOOD

Jack Brannan, Pasadena, Calif., assignor to Trade-Wind
Motorfans, Inc., Pica Rivera, Calif., a corporation of
California

Filed May 8, 1961, Ser. No. 65,070

Term of patent 3½ years

(Cl. D81—25)

FIG. 1.

FIG. 2.

FIG. 3.

FIG. 4.

FIG. 1 is a front elevational view of a cooking range hood, showing my new design with the cross-hatching on the central band representing a quilted texture, it being understood that said texture extends along the full length of the central band;

FIG. 2 is a top plan view thereof;

FIG. 3 is a bottom plan view thereof; and

FIG. 4 is an end elevational view thereof.

The characteristic features of my design for the cooking range hood disclosed reside in the specific overall configuration of the tapered front and angled step-like

portion, in combination with the quilted texture on the upper band, as best illustrated in FIGS. 1 and 4.

I claim:

The ornamental design for a cooking range hood, as shown and described.
